[57] CLAIM

The ornamental design for a protector for an electrical connecting part, as shown and described.

DESCRIPTION

FIG. 1 is a perspective view of the protector for an electrical connecting part according to the present invention;

FIG. 2 is a perspective view in the inverted state of FIG. 1 of the protector for an electrical connecting part;

FIG. 3 is a top plan view thereof;

FIG. 4 is a bottom plan view thereof;

FIG. 5 is a front end elevational view thereof;

FIG. 6 is a right side elevational view thereof, the left side elevational view being a mirror image thereof; and, FIG. 7 is a rear end elevational view thereof.

FIG. 1

FIG. 2

FIG. 3**FIG. 4****FIG. 5****FIG. 6****FIG. 7**
